US00D988780S

(12) **United States Design Patent** (10) **Patent No.:** **US D988,780 S**
Till (45) **Date of Patent:** **** Jun. 13, 2023**

(54) **COOKING POT**

(71) Applicant: **Primus AB**, Örnsköldsvik (SE)

(72) Inventor: **Staffan Till**, Solna (SE)

(73) Assignee: **Primus AB**, Örnsköldsvik (SE)

(**) Term: **15 Years**

(21) Appl. No.: **29/781,394**

(22) Filed: **Apr. 29, 2021**

Related U.S. Application Data

(62) Division of application No. 29/718,707, filed on Dec. 27, 2019.

(57) **CLAIM**

The ornamental design for a cooking pot, as shown and described.

DESCRIPTION

FIG. 1 is a perspective view of a cooking pot according to our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines in the drawings depict portions of the cooking pot that form no part of the claimed design.
